JP 2011235351 A 11/2011

Primary Examiner — Patricia Palasik

(74) Attorney, Agent, or Firm — Buchanan Ingersoll & Rooney PC

(57) **CLAIM**

The ornamental design for a molding die for pipe bending, as shown and described.

DESCRIPTION

FIG. 1 is a left side, front and top perspective view of a molding die for pipe bending showing my new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof; and,

FIG. 7 is a bottom plan view thereof.

1 Claim, 4 Drawing Sheets---
